UNITED STATES PATENT OFFICE.

ORVILLE L. LEACH, OF PROVIDENCE, RHODE ISLAND.

DESIGN FOR A WHEEL.

SPECIFICATION forming part of Design No. 33,648, dated December 4, 1900.

Application filed November 9, 1900. Serial No. 35,986. Term of patent 14 years.

To all whom it may concern:

Be it known that I, ORVILLE L. LEACH, a citizen of the United States, residing at Providence, in the county of Providence and State 5 of Rhode Island, have invented and produced a certain new and original Design for Wheels; and I do declare the following to be a full, clear, and exact description of the invention, such as will enable others skilled in the art to which it 10 appertains to make and use the same.

The invention relates to a new and original design for a wheel; and it consists of the design shown in the accompanying drawing, in which I have illustrated my invention in a 15 plan view.

The leading feature of the design comprises the radiating spokes *a*, which extend from the hub *b* to the rim of the wheel *c* and have angular V-shaped offsets *d*.

What I claim is—

The design for a wheel as herein shown and described.

In testimony whereof I have hereunto set my hand in presence of two subscribing witnesses.

ORVILLE L. LEACH.
